UNITED STATES PATENT OFFICE.

HENRY C. RITTERSON, OF JERSEY CITY, NEW JERSEY.

DEVICE FOR FASTENING DOORS, WINDOWS, AND THE LIKE.

Application filed October 5, 1927. Serial No. 224,212.

This invention relates to devices for fastening doors, windows and the like and has particular reference to devices for holding doors or windows ajar in different positions for ventilation.

5 One of the objects of the invention is to provide an apparatus of the kind mentioned which is rugged and noiseless for ships and trains, although it is at the same time suitable for use in houses and other buildings where anything of the kind may be needed.

10 Another object of the invention is to provide a device of the kind mentioned which cannot be detached or disconnected from the outside even though the door or window is open as far as the device will permit it to go.

15 With the foregoing and incidental objects in view the invention consists in a novel construction and arrangement of parts, the novel features of which are pointed out in the 20 claims appended hereto, and an illustrative embodiment of which is shown in the drawings accompanying and forming a part of this specification.

25 In said drawings:

Fig. 1 shows in elevation the various parts of the apparatus in the positions they occupy when the device is not in use.

30 Fig. 2 is a top plan view partly in section showing the parts in the positions they occupy when the device has been operated to hold a door ajar.

35 Fig. 3 is a side view of the apparatus with the parts in the same positions as they occupy in Fig. 2.

Fig. 4 is a section on the line 4—4 in Fig. 1.

Fig. 5 is a section on the line 5—5 in Fig. 1.

Described in general terms the apparatus shown in the drawings comprises two plates, 40 one of which is secured by screws or the like to the door jamb and the other is similarly fastened to the door. Each of these plates has a dove-tail member adapted to be engaged by a dove-tail groove in the base of a co-operating part of the apparatus so as to 45 permit a sliding engagement of the parts. In each instance the base of the member carrying the dove-tail groove is large enough to cover the screws used for attaching the plates to the door and door jamb, thereby 50 making it impossible to get at the attaching member until the parts have been disconnected by disengaging the dove-tail and dove-tail groove.

55 In order to prevent an accidental disconnection of the dove-tailed parts on both the

door and the door jamb small locking screws are used to hold the two parts in engagement. These locking screws are preferably below the adjacent surfaces of the connected parts 60 and cannot readily be located and removed while the door is locked ajar. Even if they could be removed the organization is such that the dove-tailed parts cannot be disengaged from the outside. In order to contribute further to the security of the apparatus, each of the locking screws may be provided with a drop of solder on its head to cover and conceal the screw slot. If the solder is used as suggested, a new slot can be 65 cut in the solder across the head of the screw when it is desired to remove the locking screw preparatory to disconnecting the dove-tailed parts.

The device in the drawings also comprises 75 an arm or link which has a ball-socket connection with the parts attached to the door frame, with the adjacent walls of the socket so shaped as to limit movement of the arm or link to horizontal and vertical planes. The 80 movement in the horizontal plane is to permit engagement of the arm or link with a lock bolt and movement of the door to different positions, while the movement in the vertical plane is to permit swinging the arm or link 85 down out of the road when the apparatus is not in use. A spring co-operating with the ball in the ball and socket joint serves to insure frictional engagement of the ball and socket and cooperates with a leaf spring latch 90 engaging the arm or link when the latter is depressed in a vertical plane to hold the arm or link from rattling when the apparatus is not in use.

Describing the apparatus more in detail 95 and with particular reference to the drawings, the door jamb 10 and door 11 are respectively equipped with plates 12 and 13, fastened in position by means of screws 14. The plates are counter-sunk to accommodate 100 the heads of the screws so that the heads are flush or below the adjacent surfaces of the plates.

The plate 12 is provided with a dove-tail 105 16 which tapers slightly relative to the edge of the door jamb. Associated with the plate 12 is a member 17 carrying in its base a dove-tail groove 18 cooperating with the dove-tail 16. The base of the member 17 is of sufficient extent to cover and conceal the screws 14 110 when the member is in position on the plate 12.

In order to prevent accidental or unauthor-

ized disconnection of the member 17 and plate 12, both the member and plate are provided with holes for a small screw 21. The member 17 is counter-sunk so that the head of the screw 21 is below the adjacent surface and, as before stated generally, the head of the screw 21 may be given a drop of solder so as to cover and conceal the slot in its head.

The member 17 is shaped to form a socket 22 in which is mounted a ball 23 on the end of an arm or link 24. Co-operating with the ball 23 is a spring 25 which tends at all times to hold the ball in good frictional contact with the interior of the socket 22.

The portion of the element 17 which contains the socket 22 is cut away as shown at 27 and 28 to clear a reduced portion 29 on the arm 24. In fact, the lower part of the socket is cut out deeply enough (as shown at 31) to permit swinging the arm 24 down in a vertical plane to a vertical position (as shown in Figs. 3 and 5) when the device is not in use.

Fastened between the plate 12 and the member 17 is an element 32, the other end of which is secured to the door jamb by a screw 33. Integral with the member 32 are two leaf-springs 34 suitably shaped to engage with a slot 35 extending substantially the full length of the arm 24. The parts of the springs 34 which engage the arm 24 are so shaped as to hold the arm in vertical position with a portion 36 thereof in firm engagement with the bottom of a slot 37 in the member 17 thereby assisting in the prevention of rattling or vibrating.

The plate 13 attached to the door 11 carries the grooved part of the dove-tailed connection 38 (Fig. 4) between the plate and a bracket 39, the base of the bracket 39, being large enough to cover and conceal the screws 14 for attaching the plate 13 to the door 11. After the members of the dove-tail are engaged a screw 40 is put in position to prevent disconnecting the bracket from the plate. The screw 40 may, as previously mentioned in connection with the screw 21, have its head beaded with solder after it is in position so as to increase the difficulty of removing the screw.

The bracket 39 carries at its outer end a cylindrical member 41 in which is slidably mounted a bolt 42. The cylindrical portion 42 is provided with two cam slots 43 and 44 to accommodate the shaft of an operating handle or knob 45 riveted in the bolt 42. The construction of the cam slot 43 is such that if the handle 45 is operated to and fro in the slot the bolt will be given a reciprocating as well as a rotary motion. The slot 44 will act in the same way, but is only provided so that the same bracket 39 can be used in connection with a door opening at the right-hand side or in cases where, for some reason, it might be desirable to mount the bolt on the door jamb instead of upon the door.

The bolt 42 has a reduced portion 47 of

sufficient diameter to engage rather closely with the slot 35 in the arm or link 24. The slot 35 has a widened portion 51 which is preferably circular in shape and of a diameter which is only a little greater than a head 52 of the bolt 42. In order to engage the bolt with the slot 35, it is necessary first to close the door and then swing the arm 24 to pass the circular opening 51 over the head 52 of the bolt, after which movement of the door 75 will cause engagement of the reduced portion 47 of the bolt with the slot 35. After the door has been moved to the desired position the handle 45 is operated, thereby causing the bolt 42 to be moved endwise to clamp the 80 arm 24 between the head 52 of the bolt and the adjacent surface of the bracket 39. The door can be partially closed by reversal of the operation of the members until the new position is secured, after which the door may 85 be again locked in position, or a further movement in the closing direction will enable disconnecting the arm 24 when it is not necessary to use the apparatus.

The arm 24 may be made of any desired 90 material, although it is of course advantageous to use materials which cannot easily be cut or bent by someone who is attempting to burglarize a room.

While the embodiment shown and de- 95 scribed is admirably adapted to fulfill the purposes primarily set forth, it is obvious that the invention is capable of various embodiments, with suitable modifications and changes, all coming within the scope of the 100 claims which follow.

What is claimed is:

1. A door ajar fastener comprising a jamb plate, a link member having a ball and socket connection at one of its ends with the jamb plate, said connection being constructed to confine the movements of the link member to movement in a horizontal plane or to movements in a vertical plane, a door bracket, a sliding bolt in the bracket provided with 105 means for engaging the link to clamp the link and bracket together in various positions of the door, means for operating the bolt for the purpose stated, and devices for 110 yieldingly holding the link in vertical position when the link is not in use.

2. In an apparatus of the character described, the combination with the frame surrounding an opening and a movable closure for the opening of a plate fastened by means 115 of screws or the like to the frame adjacent the opening, a member having a dovetail and dovetail groove connection with said plate and constructed to cover the fastening screws for the plate, a plate attached by screws or the like to the closure, a member having a dovetail and dovetail groove connection with the plate last mentioned, devices carried by the two members constructed to be engaged and then 125 operated to fasten the closure in different 130

positions with respect to the frame, and means whereby the fastening operation may be effected.

3. In an apparatus of the character described, the combination with the frame surrounding an opening and a movable closure for the opening, of a plate fastened by means of screws or the like to the frame adjacent the opening, a member having a dovetail and dovetail groove sliding connection with said plate and constructed to cover the fastening screws for the plate, an arm having a ball and socket connection at one of its ends with said member, said connection being constructed to limit movement of the arm to movement in horizontal and vertical planes, a spring in the socket yieldingly engaging the ball, a plate attached by screws or the like to the closure, a member having a dovetail and dovetail groove connection with the plate last mentioned and constructed to cover the attaching screws therefor, a bolt supported by the last mentioned member having a portion thereof constructed to engage and grip the pivoted arm, and means for operating the bolt to grip and release the arm.

4. In an apparatus of the character described, the combination with the frame surrounding an opening and a movable closure for the opening of a plate fastened by means of screws or the like to the frame adjacent the opening, a member comprising a base large enough to cover the attaching screws and slidably connected with said plate with provisions for limiting the sliding member relative to the opening, an arm having a ball and socket connection with said member and a slot extending the greater part of the length of the arm, a bracket secured to the closure, a bolt movable in the bracket and having an enlarged head cooperating with the slotted portion of the arm, and means for operating the bolt to clamp the aforesaid arm between the enlarged head of the bolt and the bracket.

45 5. In an apparatus of the character described, the combination with the frame surrounding an opening and a movable closure for the opening, of a plate fastened by means of screws or the like to the frame, a member large enough to cover the attaching screws and slidably connected with said plate with provisions for limiting the sliding movement of the member relative to the opening, an arm having a ball and socket connection with said member and a slot extending the greater part of the length of the arm, said slot having a widened portion in its end nearest the ball and socket, a bracket secured to the closure, a bolt movable in the bracket and having an enlarged head to be passed through the enlarged portion of the aforesaid slot and the bolt then engaged with the slot by movement of the closure, and means for operating the bolt to clamp the aforesaid arm between the enlarged head of the bolt and the bracket.

6. A door ajar stop comprising a plate fastened by means of screws or the like to the frame adjacent the opening, a member slidably attached to said plate large enough to cover the attaching screws with cooperating provisions for limiting the extent of sliding movement of the member, an arm having a ball and socket connection at one of its ends with said member, said connection being constructed to limit movement of the arm to movement in horizontal and vertical planes, means comprising a leaf spring for holding the arm in a vertical position when engaged with the spring, a spring in the socket cooperating with the ball to yieldingly hold the ball and socket in engagement, a plate fastened by screws or the like to the closure, a member having a sliding engagement with the plate last mentioned with provisions for limiting the sliding movement of the member in one direction relative to the plate, a bolt movably supported by the last mentioned member, means moving with the bolt and operable to grip the aforesaid arm to lock the closure in different positions with respect to the frame, and means whereby the bolt may be operated to effect the locking and unlocking operations.

7. In a device of the character described, a plate fastened by screws or the like to the door jamb and carrying one member of a dovetail connection, a bracket carrying the other member of a dovetail connection in its base, said base being of sufficient extent to cover the attaching screws for the plate when the members of the dovetail are fitted together, a screw preventing disengagement of the dovetail members, a socket in the bracket cut away at the sides and bottom, a link having a ball on one end engaged in said socket and having the body thereof constructed to engage the cuts in the sides of the socket when the link is swung in a horizontal plane and with the cut at the bottom of the socket when the arm is swung in a vertical plane, a spring in the socket cooperating with the ball on the link to hold the ball against the interior of the socket in all positions of the link, a plate secured to the door by screws or the like and carrying one member of a dovetail connection, a bracket carrying the other member of the dovetail connection on its base and having the base large enough to conceal the attaching screws for the door plate when the two members of the dovetail are fitted together, a locking screw for preventing disengagement of the two members of the dovetail, a bolt mounted in the bracket last mentioned and constructed to engage the aforesaid link and clamp same against the bolt bracket, and means for effecting movements of the bolt to clamp and unclamp the link.

In testimony whereof I hereto affix my signature,

HENRY C. RITTERSON.
